UNITED STATES PATENT OFFICE

105,686

DESIGN FOR A DRESS

Samuel Bieber, New York, N. Y.

Application June 9, 1937, Serial No. 69,744

Term of patent 3½ years

To all whom it may concern:

Be it known that I, Samuel Bieber, a citizen of the United States of America, residing in Manhattan, county of New York, and State of New York, have invented a new, original, and ornamental Design for a Dress, of which the following is a specification, reference being had to the accompanying drawing, forming part thereof, wherein,

The characteristic feature of my design resides in the Velveray trim on the dress, which trim consists of a series of dots arranged in scalloped formation in the specific configuration as shown.

I claim:

The ornamental design for a dress, substantially as shown and described.

SAMUEL BIEBER.
